LIQUID STERILIZER

Ralph E. Bitner, New York, N. Y.

Application January 24, 1940, Serial No. 315,345

4 Claims. (Cl. 99—253)

This application is a continuation in part of applicant's prior application, Serial No. 122,305, filed January 25, 1937, now Patent No. 2,189,279.

The present invention relates to liquid sterilizers, which use a combination of ultra-violet light and high frequency electrical currents for their sterilizing action, and it more particularly relates to convenient and efficient structures for subjecting a liquid to both of the above sterilizing actions at the same time.

The principal object of the present invention is to provide a structure by which liquids such as water, milk, or beer may conveniently be acted upon by high frequency currents and at the same time radiated by ultra-violet light.

Another object of the invention is to provide a structure which uses the same high frequency generator to supply the power for the ultra-violet radiator and the high frequency field.

Another object of the invention is to provide a structure in which the ultra-violet radiator may easily be removed from the sterilizer unit.

Another object of the invention is to provide a structure which may be inserted in a pipe line and perform its sterilizing action during the steady uninterrupted flow of the liquid.

Still another object is to provide a sterilizer which is closed to the outside air and completes its sterilizing action without danger of oxidation.

Other objects and structural details of the invention will be apparent from the following description when read in connection with the accompanying drawings, wherein,

Fig. 1 is a sectional view of one form of the sterilizer showing the method of mounting the ultra-violet radiator.

Fig. 2 is a cross sectional view taken along line 2—2 of Fig. 1.

Fig. 3 is a cross sectional view taken along line 3—3 of Fig. 1.

Fig. 4 is a sectional view of a second form of the sterilizer in which a different kind of ultra-violet radiator is used.

Fig. 5 is a partial elevational view showing intake pipe in section.

Fig. 6 is a cross sectional view taken along line 6—6 of Fig. 4.

Referring now to Figs. 1, 2, and 3, a pipe conduit 10 is employed to hold the ultra-violet radiator and the means which subject the liquid to a high frequency field. At the upper end of the conduit 10 a T joint 11 is attached so that the liquid may be easily admitted to the sterilizer.

The top end portion of the conduit is formed with a shoulder 12 and an internal thread 13 so

that a tube base 14 may be positioned in the end portion and secured therein, forming a liquid tight seal.

The ultra-violet radiator tube 15 is similar to one of the radiator tubes shown and described in the above mentioned application, now Patent No. 2,189,279, and is characterized by the absence of lead-in wires, the provision of external electrodes and high frequency electrical power supply. Usually the tubes are made of quartz because of the transparency to ultra-violet rays but glass tubes may be used instead, provided a sufficient amount of germ killing radiation can be obtained from them. The radiator tube 15 is made with an annular jacket 16 surrounding the central light producing portion and at the upper end, a bulb 17 is provided to afford a more secure means of support in the base 14.

An external electrode is formed around the bulb 17 by first covering it with a metallic shell 18 and then filling the intervening space between the two with molten lead to insure a tight conducting sheath. The radiator tube 15 is then placed in an insulator cup 20 as indicated in Fig. 1 and sealed in proper alignment by some melted insulating material 21 such as sulphur. This construction provides a liquid tight seal and a firm unyielding support for the radiator tube. The top portion of the shell 18 extends above the level of the insulating material 21 so that electrical contact may be made by means of a spring clip 22.

The insulating cup 20 is firmly secured in the conduit by a tubular clamping member 23 which is threaded to fit the threaded portion 13. An insulating disk 24 which may be made of Bakelite or hard rubber is secured to the clamp 23 in order to support the spring clip 22 and its binding post 25.

At the lower end of the radiator 15, a second bulb 26 is formed similar to the upper bulb but not so large. A conducting clamp 27 is placed around the bulb 26 to act as the second external electrode for the radiator tube and to this clamp a plurality of conducting vanes 28 are soldered (see Fig. 2). A similar clamp 29 is placed at the upper end of the vanes for mechanical purposes only and does not have to be made of conducting material.

Integral with the conduit and formed by die casting or other known methods is a plurality of inwardly extending partitions 30 which are alternately spaced with respect to the vanes 28 to form a series of parallel passageways, each bounded by two flat surfaces which provide a

means for the efficient transfer of high frequency currents.

A source of high frequency power is schematically indicated at 31 with output leads connected to the binding post 25 and the conduit 10. The path of the current may be traced as follows: From the generator 31 to the binding post 25 and clip 22, to the brass shell 18 and lead insert 19, through the wall of the bulb 17, down the central portion of the radiator 15 to the lower bulb 26, through the walls of this bulb to the lower conducting clamp 27, thence to the vanes 28, through the liquid in the conduit to the partitions 30 and back to the generator 31.

As was explained in the above mentioned Patent 2,189,279, the designation "high frequency" is applied to a source of electric power when the frequency is at least one million cycles per second. At this frequency and with sufficient voltage, the current will easily pass through the quartz walls of the upper and lower bulbs 17 and 26, and through the liquid between the vanes 28 and partitions 30. In accordance with common practice the radiator tube 15 is filled with approximately 8 millimeters pressure (Hg) of argon gas together with a few drops of mercury. The jacket 16 is fully exhausted to provide a heat insulation means and an annular barrier which will separate the electric discharge from the liquid flowing in the conduit.

It will be obvious from the above details of construction that any liquid flowing through the conduit will be subjected to the action of ultra-violet light and high frequency currents simultaneously.

It is a well known fact that ultra-violet light has considerable germicidal action when used alone. Also the passage of high frequency currents through a liquid (often called diathermy action) has a distinct germ killing power. When used together, the simultaneous action produces a resulting sterilizing action which is greatly in excess of the sum of the actions taken separately.

While a considerable number of liquids designed to be used in this structure have a comparatively low resistance and will permit a current to flow through their volume by conductive action, it is also possible to use high frequency currents on liquids and gases having very high insulating properties. This is due to the capacity currents which will normally flow across a dielectric when bounded by two conducting plates. It has been found that the germ killing power of condenser currents is as effective as conductive currents.

Referring now to Figs. 4, 5, and 6, a conduit 40 is employed as the sterilizing chamber and is made of any suitable insulating material. Glass or fused quartz may be used but it has been found more convenient to utilize one of the transparent synthetic resins for this purpose. These are variously known under their trade names as "Lucite," "Polysterene," and "Crystalite" and are desirable because of the ease with which they may be machined and worked with ordinary metal cutting tools.

The outer cylinder 41 is closed at both ends by washer-like pieces 42 and 43. An upper entrance pipe 44 is connected to the side wall 41 and is used to convey the liquid to be sterilized into the sterilizing chamber. A lower exit pipe 45 is attached to the conduit 41 in a similar manner and is used to convey the liquid away. Because of insulation difficulties, it has been found de-

75
sirable to construct the pipes 44 and 45 of the same insulating material as the main conduit.

Concentrically aligned with the outer cylinder 41 is an inner tube 46 made of the same material as the other conduits and sealed at its ends to the washer-like pieces 42 and 43 thereby forming a closed toroidal chamber having a central portion 48 open at each end into which may be positioned a discharge tube 47 which when properly excited 10 will become a radiator of ultra-violet light. This radiator may be similar to the one shown in Fig. 1 but in Fig. 4 an alternate type is shown to illustrate the possibilities of this type of sterilizing unit. The envelope of this radiator must be 15 transparent to ultra-violet rays and must be filled with a suitable substance capable of emitting ultra-violet light when properly energized. The type indicated in Fig. 4 is provided with internal electrodes 48 and lead-in wires 49. By using this construction, low frequency electrical power (60 cycles per second) may be used to light the radiator 47 and thus make it independent of the high frequency field supply. Fig. 20 4 shows connecting wires 50 which deliver power from a secondary 51 of a constant current transformer 52 having a primary winding 53 connected directly to a standard 110 volt A. C. lighting supply. The constant current transformer 52 is well known in the art and is used to supply neon tube 25 signs and other similar discharge lamps.

Within the toroidal chambers formed by conduit 41, inner tubing 46 and the end pieces 42 and 43, there are placed two helical conductors 54 and 55 alternately spaced. One of these conductors 54 is connected directly to the top end washer 42 and winds downward in the form of a convolute screw to the lower end washer 43.

The second conductor 55 is formed in the same manner as the first but is shorted by one full turn 40 and is positioned as shown in Fig. 4 midway between the turns of the first conductor. With the two helical conductors in place there results two spiral spaces with common openings at the upper and lower pipes 44 and 45, each space bounded 45 at its upper face by one conductor and at its lower face by the other conductor. If, now, a liquid is injected into these spiral spaces and electrical potential applied to the conductors, two electrical cells will result.

At all points within the toroidal chamber, the surfaces of the conductors 54 and 55 are at an angle of 90° from the axis of the radiator 47 and therefore present an unobstructed path for the ultra-violet rays to travel parallel to the conductor surface and irradiate the entire space between adjacent conductors.

A high frequency oscillator 56 is represented in Fig. 4, which may be any one of a number of well known devices for generating sustained high frequency electrical currents. Oscillator leads 57 convey the electrical power to the two helical conductors 54 and 55 thereby energizing the electrical cell hereinbefore described and causing high frequency currents to flow through the liquid between the conductors.

It will be obvious that the liquid in the structure shown in Figs. 4, 5, and 6 will be acted upon simultaneously by ultra-violet radiation and high frequency currents in exactly the same manner as the liquid in the structure shown in Figs. 1, 2, and 3. The sterilizing action should be the same in either case. The two structures are shown to offer a more flexible and diversified system which may be changed to suit the characteristics of the liquids to be sterilized.

When sterilizing liquids which have a very low resistance it may become necessary to rely on capacity currents only and in such cases the conductive plates (54 and 55 in Fig. 4 and 28 and 30 in Fig. 1) may be encased or covered with a layer of insulating varnish or resin.

While I have described what I consider to be a highly desirable embodiment of my invention, it is obvious that many changes in form could be made without departing from the spirit of my invention, and I therefore, do not limit myself to the exact forms herein shown and described, nor to anything less than the whole of my invention as hereinbefore set forth, and as hereinafter claimed.

I claim:

1. A sterilizer of the class described comprising in combination a conduit, an ultra-violet radiator, an electrical cell, and means for subjecting a liquid to the simultaneous action of ultra-violet rays and high frequency electrical power; said ultra-violet radiator comprising an elongated sealed envelope transparent to ultra-violet rays, a substance capable of emitting ultra-violet light within said envelope, an electrode at each end of said envelope, and a source of electrical power for energizing said substance; said electrical cell comprising a plurality of conducting plates arranged in two groups, one group disposed about said envelope and connected to one of said electrodes, the other group positioned in interspaced alternate arrangement with the plates of the first group and connected to the source of electrical power, and means for permitting the liquid to flow through said conduit between said plates.

2. A sterilizer comprising in combination, a conduit, an ultra-violet radiator within said conduit, an electric cell also within said conduit, and sterilizing means for subjecting a liquid to the simultaneous action of ultra-violet rays and high frequency electrical power; said ultra-violet radiator comprising an elongated sealed envelope transparent to ultra-violet rays, a substance capable of emitting ultra-violet light within said envelope, an evacuated jacket transparent to ultra-violet rays surrounding the central portion of said envelope and an electrode at each end of said envelope; said electric cell comprising a plurality

of conducting plates positioned around said envelope in parallel arrangement and connected to one of said electrodes, and a plurality of cooperating conducting surfaces arranged parallel to said plates and secured to said conduit; said sterilizing means comprising a source of high frequency electrical power connected between said conduit and the other electrode.

3. A sterilizer comprising in combination, a conduit, an ultra-violet radiator within said conduit, an electrical cell also within said conduit, and sterilizing means for subjecting a liquid to the simultaneous action of ultra-violet rays and high frequency power; said electric cell comprising a plurality of conducting plates positioned around said envelope in parallel arrangement, a plurality of cooperating conducting surfaces arranged parallel to said plates in interspaced relation and secured to said conduit, and a film of insulation covering the conducting plates and conducting surfaces; said sterilizing means comprising a supply of suitable electrical power for the operation of said ultra-violet radiator and a supply of high frequency electrical power connected between said conducting plates and the conduit.

4. A sterilizer comprising in combination, a conduit, an ultra-violet radiator within said conduit, an electric cell also within said conduit, and sterilizing means for subjecting a liquid to the simultaneous action of ultra-violet rays and high frequency electrical power; said ultra-violet radiator comprising an elongated sealed envelope transparent to ultra-violet rays, a substance capable of emitting ultra-violet light within said envelope, and an electrode at each end of said envelope; said electric cell comprising a group of electrically connected conducting plates positioned around said envelope and a group of cooperating electrically connected surfaces arranged in interspaced relation to said plates; said sterilizing means comprising a supply of high frequency electrical power, the terminals of which are connected to the conducting surfaces, and one of the electrodes, and an electrical connection between the conducting plates and the other electrode.

RALPH E. BITNER.
